UNITED STATES PATENT OFFICE.

WILLIAM PINKNEY-McNEEL, OF SAN ANTONIO, TEXAS.

ELECTRIC-LAMP ATTACHMENT.

1,075,365.

Specification of Letters Patent.

Patented Oct. 14, 1913.

Application filed April 23, 1912. Serial No. 692,587.

To all whom it may concern:

Be it known that I, WILLIAM P. MCNEEL, a citizen of the United States, residing at San Antonio, in the county of Bexar and 5 State of Texas, have invented a new and useful Electric-Lamp Attachment, of which the following is a specification.

The present invention relates to improvements in electric lamp attachments, the primary object of this invention being the provision of a lamp socket attachment or supporting means in combination with a switch, whereby the current energizing the filament of an incandescent lamp is so controlled as 15 to produce different degrees of incandescence in the filament and thus produce different degrees of radiance to produce a dim or a high light as may be desired.

A further object of the present invention 20 is the provision of a lamp socket attachment having a receptacle therein in which is mounted an individual resistance, a switch having three terminal wires being disposed in operable relation to said resistance and 25 the contact plates of the socket, whereby the resistance may be placed into or cut out of the line with the filament of the lamp, and thus produce a varying radiancy or incandescence to the filament.

With the foregoing and other objects in 30 view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a view showing the lamp socket attachment broken away to show the interior construction thereof, with the switch carrying member 45 in elevation, the lamp socket and lamp being connected. Fig. 2 is a section taken on line 2-2 of Fig. 1. Fig. 3 is a section taken on line 3-3 of Fig. 1. Fig. 4 is a detail view of the switch member with the cover removed therefrom. Fig. 5 is a diagrammatic view of the electrical circuit used in connection with the socket attachment and switch.

Referring to the drawings, the numeral 1 55 designates the body of insulation, preferably made of porcelain, the main portion of

which is formed circular in cross section and is provided with the upper reduced cylindrical end 2 for removable connection with a socket S. The main body portion of the 60 member 1 is covered by a metal casing 3 which carries the reduced lamp receiving sleeve 4 in which is mounted the sleeve 5 of insulating material. Disposed within the sleeve 5 of insulating material is the lamp 65 socket receiving sleeve 6, which forms one of the terminals, as is the usual practice, while disposed concentrically through the body 1 and reduced end 2, is a retaining rod or screw 7, which forms the other terminal 70 for the lamp L, the lower end of the rod 7 being insulated from the lamp socket 6 by means of the disk 8 of insulation. The threaded terminal sleeve 10 is disposed upon the reduced cylindrical portion 2 and is 75 provided with the terminal post 10', which projects within and at the upper end of the recess 11 formed in the body 1.

A contact pin 12 is connected to the sleeve 6 and projects upwardly, so that the upper end thereof is within the lower end of the recess or receptacle 11 and engages the contact plate 13 provided with the clips 14. These clips provide a means for the removable reception of the lower end of the 80 resistance strip 15 which is embedded in the spool 16 of insulation to provide a ready means for carrying the resistance strip 15 and to also insulate the same from the metal cover 3 should the same contact it when the 85 cover is in sealing position. The upper end 17 of the resistance coil is connected to a screw 18, from which is led a conductor 19 to the switch carrying member 20. This switch carrying member 20 is disposed at 90 any point within a room to permit of the easy actuation thereof for controlling the lamp L. A conductor 19 is led through the channel 21 of the switch member 20.

The switch member 20 has connected 100 therein by means of the screw 22, a plate 24 to which is pivoted the switch 25, the switch 25 being provided with an insulated handle 25' which is projected exteriorly of the switch body 20 so as to be readily operated 105 to move the free arm 27 of said switch 25 to the dotted and full line position as shown in Fig. 4. The conductor 19 is connected to the contact terminal 28 carried by the body 20 and secured in position by 110 means of the screw 29, while a conductor 30 is led to the contact plate 24 and is con-

nected thereto by means of the screw 22, thus establishing a circuit through the contacts 24 and 28 to include the resistance strip 15 with the lamp L, as clearly shown 5 in diagram in Fig. 5. The third contact plate 21 is carried by the switch body 20 and is connected by means of a screw 32 to the other conductor 33 which is led from the lamp socket 1 and thus provides a means 10 for connecting the lamp L directly to the generator G.

To more clearly show the use of the present invention, reference should be had to the electrical diagram as shown in Fig. 5, 15 in which is shown the switch 25 open, and consequently the lamp L deenergized. Should it be desired to produce a dim light or low incandescence of the lamp L, the switch 25 is operated to bridge the contact 20 plates 24 and 28 and thus close a circuit from the generator G, to the conductor 30, contact plate 24, the switch 27, the contact plate 28, the conductor 19, resistance 15, the conductor 33, the lamp L and the generator. 25 By this means it will be seen that the resistance 15, is carried bodily by the lamp attaching body 1 to be cut into the line and thereby reduce the amount of current effecting the filament of the lamp L and thus 30 produce the dim effect desired. Should, however, it be desired to throw the lamp into the line, the switch 25 is moved to the full line position Fig. 4, so as to bridge the contact plates 24 and 31 and thus cut out 35 the resistance 15, completing a circuit from the generator G, conductor 30, the contact plate 24, the switch 25, contact plate 31, conductor 30, and the lamp L. Thus the 40 full current from the generator is thrown into the lamp L and the filament thereof is energized to its full incandescence.

From the foregoing description, taken in connection with the drawings it is evident that the attachment 1 carries bodily its own 45 resistance and thus provides a means whereby any form of lamp of the incandescent

type may be attached thereto and have its filament affected to produce the high or low light without any change in the construction of the filament or the socket.

While herein is described the invention in detail, and is illustrated a combination embodying various features, which may at times be used to advantage, it is not the desire or intention of claimant to be limited to the particular arrangement shown, or to an arrangement embodying the various auxiliary features, except as particularly pointed out in the appended claim.

What is claimed is:

A lamp socket rheostat including a body of insulation provided with a recess in one wall thereof, a reduced exteriorly threaded lamp socket engaging boss carried upon the upper end thereof, a metal cap inclosing the same, a concentrically disposed rod extending through the body from end to end, the upper end being insulated from the metal cap, a metal casing inclosing the body and sealing the recess, the lower end of the same being constricted and threaded to receive the threaded end of a lamp, a metal socket fitted concentrically within the constricted end of the metal casing and insulated therefrom and also from the concentric rod, a resistance coil disposed within the recess, one terminal of the coil being electrically connected to the metal socket of the constricted portion of the casing, and three conductors one interposed between the metal socket engaging cap and the resistance, the second between the resistance and the metal lamp engaging socket and the third directly connecting the cap and socket.

In testimony that I claim the foregoing as my own, I have hereto affixed my signature in the presence of two witnesses.

WILLIAM PINKNEY McNEEL.
